UNITED STATES PATENT OFFICE.

RUSSEL G. WOODWARD, OF CHICAGO, ILLINOIS, ASSIGNOR TO UNION SPECIAL MACHINE COMPANY, OF CHICAGO, ILLINOIS, A CORPORATION OF ILLINOIS.

EDGING-GUIDE FOR SEWING-MACHINES.

1,138,343.

Specification of Letters Patent.

Patented May 4, 1915

Application filed August 6, 1909. Serial No. 511,595.

To all whom it may concern:

Be it known that I, RUSSEL G. WOODWARD, a citizen of the United States, residing at Chicago, in the county of Cook, State of Illinois, have invented certain new and useful Improvements in Edging-Guides for Sewing-Machines, of which the following is a description, reference being had to the accompanying drawing, and to the letters and figures of reference marked thereon.

The invention relates to new and useful improvements in edging guides, and more especially guides for edgings which are provided with diagonally extending cross bars.

An object of the invention is to provide a guiding device which will spread out the edging and properly position the cross bars relative to one another, so that when the edging is fed to a stitch-forming mechanism, it may be properly secured to a fabric.

A further object of the invention is to provide an edging guide which may be used to direct an edging to the under face of a fabric, spreading out the edging and properly position the cross bars thereof.

A further object of the invention is to provide an edging guide which may be readily withdrawn from the position adjacent the stitching mechanism, so that the same may be threaded with the edging.

These and other objects will in part be obvious, and will in part be hereinafter more fully described.

In the drawings which show by way of illustration, one embodiment of the invention,

Figure 1 is a front view of the forward portion of a sewing machine having my improved edging guide attached thereto; Fig. 2 is a transverse sectional view through the work support and edging guide, the feed-operating mechanism and looper mechanism being omitted for the sake of clearness; Fig. 3 is a plan view of a portion of the work support, showing the relation of the edging guide to the feed and the stitching mechanism; Fig. 4 is a similar view with the cover plate for the edging guide removed; Fig. 5 is a view from the front of the edging guide, showing the same detached from the machine; Fig. 6 is a top plan view of the edging guide, showing the manner of spreading the edging and positioning the

cross bars; Fig. 7 is a detail, showing the position of the needles and the loopers co-operating therewith; Fig. 8 is a detail, showing a section of the fabric with the edging stitched thereto.

The sewing machine, as herein illustrated, may be of any desired construction, and forms no part of the present invention.

I have shown a work support 1, an overhanging arm 2, a needle bar 3 carrying needles 4, 5 and 6. The needle bar is reciprocated in the usual manner by the needle lever 7. The presser foot 8 is carried by the presser bar 9, and may be of any desired construction.

The work support 1 has the usual depending apron 10, and said work support is carried by the bed plate 11. The feed dog 12 may be of the ordinary four motion type, and is provided with fabric-engaging surfaces 13. An auxiliary feed dog 14, which has a differential movement relative to the main feed dog, may also be used, if desired. These parts are of the usual construction, and will not need further description.

In making garments, it is often desired to provide the same along the edge or sometimes in the body thereof, with an edging which has cross bars underneath which a ribbon may be inserted, or through which a ribbon may be threaded. For example, in the necking of underwear, it is desirable to provide the neck portion of the garment with an edging of the above character. My invention is directed to a guiding device which will guide an edging of this character to a stitching mechanism. It is sometimes desirable to stitch the edging on the under face of the garment, and it is also sometimes desirable to stitch the edging on the upper face of the garment. As herein illustrated, I have shown a guiding device for guiding an edging so that the same may be stitched to the under face of the garment. It will be understood, however, that the edging guide may be disposed above the fabric and operate to guide an edging to the upper face of the fabric.

My improved edging guide comprises spaced plates 15 and 16, which are held separated by spacing bars 17, 17.

As herein shown, the work support is cut away as at 19, to receive my edging guide.

The edging guide is pivotally mounted on a bracket 20, which is secured to the depending apron 10 of the work support by suitable screws 21. A pivot bolt 22 extends through 5 ears bent up from the bracket 20, and the side members 15 and 16 of the edging guide. The side members 15 and 16 are provided with inwardly projecting parts 23, which extend to a point in front of and adjacent 10 the needle slots 24 in the throat plate. The needle slots 24 are adapted to receive the needles 5 and 6, and the needle slot 25 receives the needle 4.

The inwardly projecting portions of the 15 members 15 and 16 are provided with cross bars 26, 27, 28, 29 and 30. The cross bar 26 on its upper face has an upwardly projecting curved portion 31, which terminates in recesses 32, 32. The cross bar 27 has a similarly curved portion 33, which projects downwardly. The cross bars 28 and 30 have curved portions 31 projecting upwardly; while the cross bar 29 has a curved portion 20 projecting downwardly.

25 The curved portion of the cross bar 28 is formed on a slightly larger radius than the curved portion of the cross bar 26, and the recesses 32, in which the curved portion terminates, are arranged slightly closer to 30 the side bars 15 and 16. The curved portion of the cross bar 30 is formed on a slightly larger radius than the curved portion of the cross bar 28, and the recesses 32 of the cross bar 30 are still a little closer to the side members 15 and 16.

35 The curvature of the cross bar 27 is slightly greater than that of the cross bar 26, and slightly less than that of the cross bar 28; while the curvature of the cross bar 29 40 is slightly greater than that of the cross bar 28, and slightly less than that of the cross bar 30.

The edging 34, as shown in Fig. 8, comprises side portions 35 and diagonally arranged cross bars 36. In guiding this edging to the stitch-forming mechanism, it is led over the cross bar 26; underneath the cross bar 27; over the cross bar 28; under the cross bar 29 and over the cross bar 30, as 45 shown in Fig. 2, so that as the edging is drawn through the guide, the same will be presented to the curved faces of the cross bars. This edging, as it comes from the roll is very much distorted, and drawn together. 50 As it passes over the cross bar 26, the curved portion will crowd the side parts 35 of the edging down into the recesses 32, and separate slightly said side portions of the edging. The cross bars as they pass over the 55 curved portions will also be put under tension, and will assume their proper position diagonally of the side portion of the edging. 60 As the edging continues over the varying curved surfaces and the varying width slots 65 32, it will be properly spread and the cross

bars will be properly positioned, so that as the edging leaves the guiding device, it is properly shaped to be secured to the fabric.

A cover plate 37 is secured to the work support 1 by a slot and screw connection 38. 70 This cover plate extends over the edging guide, and will serve as a rest on which to guide a body fabric, to which the edging is to be stitched. Said cover plate may, if desired, be provided with an edge guide 39 for 75 guiding the edge of the material.

As herein illustrated, I have shown my stitch-forming mechanism as provided with needles 5 and 6. These needles are so located that one edge of the edging will pass underneath the fabric between said needles, so that one of the needles will enter the edging and the other pass at one side thereof. 80

Coöperating with the needles 5 and 6 is a looped 40, which will lay cross threads 41 across the edge of the edging, as shown in Fig. 8. The needle 4 is so positioned as to pass through one of the side members 35 of the edging, and a looper 42 coöperates therewith to secure the edging to the fabric. 90

When it is desired to thread the edging into the guide, the cover plate may be removed and the guide swung about its pivotal support 22, so that the edging may be readily inserted, after which the guide is 95 swung back to its normal position and the cover plate replaced.

While I have shown my edging guide so disposed as to guide an edging to the under face of the fabric, it is evident, as above 100 noted, that said edging guide may be supported above the work support and guide an edging to the upper face of the fabric.

The inwardly projecting side members 15 and 16 are gradually narrower as they approach the stitching point, thus forming a tapering lower face 23^a. The ends of the side members adjacent the stitching point are merely the width of the side bar 30. By this construction I have provided a clearance 105 for the looper mechanism and am able to bring my edge guide very close to the stitching point.

Having thus described my invention, what I claim as new and desire to secure 115 by Letters Patent, is:—

1. The combination with a stitch forming mechanism and a feeding mechanism, of a guiding device for guiding an edging containing oppositely extending diagonally arranged cross bars to said stitch forming mechanism, said guiding device having means for alining the opposed apices of each pair of apices of the cross bars, whereby each pair of opposed apices will be fed to 120 the stitch forming mechanism in a line at right angles to the line of feed.

2. The combination with a stitch forming mechanism and a feeding mechanism, of a guiding device for guiding an edging con- 130

taining oppositely extending diagonally arranged cross bars, to said stitch forming mechanism, said guiding device having means for alining and spreading the opposed apices of each pair of apices of the cross bars whereby each pair of opposed apices will be fed to the stitch forming mechanism in a line at right angles to the line of feed and in proper spaced relation to be engaged by the stitch forming mechanism.

3. The combination with a stitch forming mechanism and a feeding mechanism, of a guiding device for guiding an edging containing oppositely extending diagonally arranged cross bars to said stitch forming mechanism, said guiding device having means for engaging in the respective openings between the opposed apices of each pair of apices of the cross bars, whereby the pairs of opposed apices will be stretched laterally and simultaneously alined so as to be fed to the stitch forming mechanism in a line at right angles to the line of feed.

20 4. In a guiding device for guiding an edging containing oppositely extending diagonally arranged cross bars, a pair of spaced side members between which the edging is to be fed, and means disposed between said side members for engagement with the edging to aline the opposed apices of each pair of apices of the cross bars in a line at right angles to the line of feed of the edging.

35 5. The combination with a stitch-forming mechanism, of a device for guiding an edging having diagonally arranged cross bars, to said stitch-forming mechanism, including normally stationary guiding members over which the edging may be drawn, said members having curved guiding faces terminating in guiding recesses which spread the edging and properly position the cross bars thereof.

45 6. The combination with a stitch-forming mechanism, of a device for guiding an edging having diagonally arranged cross bars, to said stitch-forming mechanism, including guiding members having curved guiding faces terminating in guiding recesses for spreading the edging and properly positioning the cross bars thereof, said curved guiding faces varying in curvature toward the delivery end of the guide.

55 7. The combination with stitch-forming mechanism, of a device for guiding an edging having spaced cross bars to said stitch-forming mechanism, including normally stationary spaced members having respectively upwardly and downwardly curved guiding faces terminating in guiding recesses.

60 8. The combination with stitch-forming mechanism, of a device for guiding an edging having spaced cross bars, to said stitch-forming mechanism, including spaced mem-

bers having respectively upwardly and downwardly curved guiding faces terminating in guiding recesses, said curved guiding faces varying in curvature toward the delivery end of the device.

70 9. An edging guide including in combination, spaced side members, cross bars supported thereby, said cross bars having curved guiding faces located on the opposite sides of the alternate cross bars, the curvature of said faces varying toward the delivery end of said guide.

75 10. An edging guide including in combination, spaced side members, spaced cross bars carried thereby, said cross bars having respectively upwardly and downwardly projecting curved guiding faces terminating in guiding recesses, said curved guiding faces varying in curvature toward the delivery end of the guide, and said guiding recesses being gradually spaced further apart toward the delivery end of the guide, whereby the side portions of an edging running in said recesses may be spread and the cross bars thereof properly positioned relative to the side portions of the edging.

80 11. A sewing machine including in combination a work support, a presser foot, stitch forming mechanism, said work support being cut away in front of the stitch forming mechanism and to a point directly under the forward end of the presser foot, and an edging guide located in said cut away portion of the work support and having spaced bars provided respectively with upwardly and downwardly projecting convex surfaces lying in parallel planes for spreading and positioning the cross bars of the edging and holding the same until engaged by the presser foot.

85 105 12. A sewing machine including in combination, stitch-forming mechanism, a work support, said work support being cut away in front of the stitch-forming mechanism, an edging guide located in said cut away portion of the work support and having spaced bars for guiding and positioning the cross bars of an edging, a cover plate adapted to cover the opening in said work support.

90 110 13. A sewing machine including in combination, stitch-forming mechanism, a work support, said work support being cut away in front of the stitch-forming mechanism, an edging guide located in said cut away portion of the work support and having spaced bars for guiding and positioning the cross bars of an edging, a cover plate adapted to cover the opening in said work support, and an edge guide carried by said cover plate.

95 115 14. A sewing machine including in combination, stitch-forming mechanism, a work support having a cut away portion in front of the stitch-forming mechanism, an edging

- guide located in said cut away portion, means for pivotally supporting said edging guide, and a cover plate for covering the opening in said work support.
- 5 15. A sewing machine including in combination a work support, a presser foot stitch-forming mechanism including a pair of needles, a looper coöperating with said needles for forming cross stitches between 10 the same, a third needle spaced from said pair of needles, a looper coöperating with said third needle, an edging guide located beneath the work support and extending to a point adjacent the front end of the presser 15 foot for guiding an edging to a lower face of a fabric, and directing one edge of said edging between said pair of needles, whereby said edge is covered with the cross stitches.
- 20 16. A sewing machine including in combination a work support, a presser foot stitch-forming mechanism including a pair of needles, a looper coöperating with said needles for forming cross stitches between 25 the same, a third needle spaced from said pair of needles, a looper coöperating with said third needle, an edging guide located beneath the work support and extending to a point adjacent the front end of the presser 30 foot for guiding an edging to a lower face of a fabric and directing one edge of said edging between said pair of needles, whereby said edge is covered with the cross stitches, said edging guide having means for 35 properly positioning the cross bars of said edging.
17. A sewing machine including in combination a work support, a presser foot stitch forming mechanism, said work support being cut away in front of the stitch forming mechanism to a point directly under the forward end of the presser foot and
- an edging guide located in said cut away portion of the work support and extending to a point adjacent the front end of the 45 presser foot, said edging guide having means for spreading and positioning the cross bars of an edging and holding the same until engaged by the presser foot.
18. A sewing machine including in combination, a work support, stitch forming mechanism, an edging guiding means located beneath the work support and having means for straightening the edging and properly positioning the cross bars there- 55 of, said edge guiding means extending to a point adjacent the stitching mechanism, whereby the edging is held properly ex- tended substantially at the stitching point.
19. A sewing machine including in com- 60 bination, a work support, stitch forming mechanism, an edging guide comprising side members located beneath the work support and extending to a point adjacent the stitch- forming mechanism, spaced cross bars car- 65 ried by said side members, said side mem- bers tapering toward the stitching point so as to provide a clearance space underneath the same for the complemental parts of the stitch forming mechanism.
20. In combination with a sewing ma- 70 chine having a plurality of needles, an edg- ing guide for guiding an edging to the fabric, said edging guide including spaced members, each of said spaced members be- 75 ing provided with a guiding and spreading convex surface terminating in guiding re- cesses for spreading the edging.

In testimony whereof I affix my signature, in presence of two witnesses.

RUSSEL G. WOODWARD.
